UNITED STATES PATENT OFFICE

2,474,873

EYELASH CURLER

William R. Tuttle and William J. Beldue, Rochester, N. Y., assignors to The Kurlash Company, Inc., Rochester, N. Y., a corporation of New York

Application March 18, 1946, Serial No. 655,153

8 Claims. (Cl. 132—32)

1. This invention relates to eyelash curlers of the general character of that shown in our Patent No. 2,391,047 and in other prior patents, and wherein a pair of handle members are pivotally connected together, one of said handle members tending to move a movable jaw to and from a fixed jaw mounted on the other handle member.

The construction and arrangement of the several parts of these devices is such that the protrusion of the handles causes the device to occupy considerable space, with the result that these devices, while often carried in the handbag of the user, are not conveniently so carried due to the space which they occupy therein. This inconvenience in carrying the devices, interferes with their portability.

One of the objects therefore, of the present invention, is to provide an eyelash curler of the character described which will have at least one of its handle portions arranged to fold in such a manner as to materially decrease the overall width of the device, thus making the carrying of the device in a handbag, or in any other substantially small receptacle, entirely feasible.

An object of the invention is to provide means by which one of the handles can be folded upwardly and disposed within the forked end extension of the other handle, thus bringing the folding handle to a position where it is out of the way, and greatly reducing the size of the curler.

More particularly, the invention contemplates the provision of a curler having a stationary handle in which a movable handle is pivotally mounted, both handles being arcuately slotted to receive a jaw-actuating link, the slots having off-set portions into which the link may be selectively positioned to either cause the link to be actuated by pivotal movement of the movable handle or else to allow said link to remain stationary while the movable handle is pivoted to its folded position.

These and other objects are attained by the invention, a more particular description of which will hereinafter appear and be set forth in the claims appended hereto.

In the accompanying drawing, wherein an illustrative embodiment of the invention is shown, Fig. 1 is a side elevation of an eyelash curler constructed in accordance with the invention, the parts thereof being in position to cause the movable jaw to be actuated by movement of the movable handle; Fig. 2 is a side elevation of the device, showing the movable handle in its folded position; Fig. 3 is a rear view of the device, with the movable handle in its operative position; the

view being taken looking at the left side of Fig. 1; Fig. 4 is a face view of the movable handle; Fig. 5 is a side view of the fixed segment or clevis; and Fig. 6 is a top plan view of the segment or clevis.

An eyelash curler of this character includes a relatively stationary element 1 and a relatively movable element, the latter in the present construction consisting of the parts 9 and 15 arranged to be coupled or uncoupled in a manner to be described. The stationary element includes the finger loop 4 and the spaced side-by-side posts 3 and 30, the latter being formed at the top with the off-set arms 18, so that the stationary element is in the form of a yoke that is bridged at the top by the curved plate 2 constituting the fixed jaw of the device.

At 6 is shown a bracket in the form of a clevis, the same being secured between the flattened portions 5 of the posts 3 and 30 by means of the two rivets 20, so that the segmental or quadrant-shaped plate portions 7 of said clevis project from the stationary handle 1 as a fixed lateral extension thereof. Provided in each of the segmental plate portions 7 is an arcuate slot 13 having an off-set or laterally extended part 14 at one of its ends.

Pivotedly mounted between the plate portions 7 is the movable handle portion 9, the same being pivoted on the pin 8. This handle portion 9 is provided with a finger loop and at the opposite end is formed with a segmental or quadrant-shaped plate 12 formed with an arcuate slot 10. At one end the slot 10 is provided with an off-set extension 11. It will be noted that the slots 10 and 13 are not in registration, but that the off-set portion 11 of the slot 10 is in alignment with slot 13, while the off-set portion 14 of slot 13 is in alignment with the slot 10.

The movable jaw of the eyelash curler is shown at 16, the same being provided at its opposite ends with the loops 19, which are slideable on the arms 18 of the stationary handle portions 3 and 30 so that the movable jaw may be moved to and from the fixed jaw in the known manner to thereby shape the eyelashes between the jaws.

Movable jaw 16 is provided with a resilient facing 17 that is brought into contact with the lower edge of the fixed jaw when the movable jaw is raised.

The link 15 is in the form of a wire yoke having its upper ends fixedly attached to the movable jaw and its opposite end looped through the slots 10 and 13, this looped end 32 of the link 15 being positioned in either one of the off-set portions 11 or 14 of the respective slots 10 and 13 according

to whether the movable handle 9 is to be in its inoperative position or operative position.

For example, in Fig. 1 the movable handle is in its operative position and the movable jaw is raised so that its resilient facing 17 is in contact with the lower edge of the fixed jaw. It will be noted that the lower or looped end 32 of the link 15 is at this time positioned within the off-set portion 11 of the slot 10. To lower the movable jaw 16 it is merely necessary to move the handle 9 in a direction away from the fixed handle 4, and this movement causes the link 15 to be drawn downwardly by the downward swing of the segmental plate 12. Since the looped end of the link 15 is confined within the off-set portion 11 of the slot 10 in plate 12 there is an operative connection between the link and the segment 12 to cause the link 15 to be drawn down and the movable jaw brought down with it. In other words, as long as the looped end 32 of the link 15 is confined in the off-set end 11 of the slot 10 it will be apparent that any movement of the handle 9 will be transmitted to link 15 and the movable jaw raised or lowered accordingly. As the link 15 is raised or lowered as above explained, its looped end will ride freely in the slots 13.

When it is desired to fold up the handle 9 to the position shown in Fig. 2, and in dotted lines in Fig. 3, the looped end 32 of the link 15 is manually shifted out of the off-set portion 11 of slot 10 and into the off-set part 14 of the slot 13. This movement of the looped end 32 of the link can be performed while the parts of the device are in the position shown in Fig. 1, at which time the off-set portions 14 and 11 are in alignment radially of the segmental plates 7. The resiliency of the link 15 enables it to be readily sprung into either of the off-set portions of the slots.

When the looped end 32 of the link 15 is placed in the off-set portion 14 of slot 13, it will then be apparent that it is uncoupled from the segment 12 so that the movable handle 9 can then be swung on its pivot 8 without affecting the link 15, which remains stationary, and holds the movable jaw 16 in closed position relative to the fixed jaw 2. The movable handle can be swung upwardly, as shown in Fig. 2 to bring its looped end directly below the movable jaw, thus decreasing the width of the device and rendering it compact and easily carried in a handbag or the like. While the looped end 32 of the link 15 is contained in the off-set portion 14, and the movable handle is swung, the slot 10 rides freely about the looped end 32 and movement of the handle 9 to its folded position is free and unrestricted.

Through the arrangement disclosed, means is provided by which the movable handle, which normally protrudes to such an extent as to make the device somewhat inconvenient to carry in a small handbag, is folded to cause the structure to be rendered compact. At the same time, the folding of the handle as above explained, causes the movable jaw to be locked in its closed position, whereby the entry of objects between the jaws with resultant damage or injury to the contacting surfaces of the jaws is prevented.

While we have shown one embodiment of the invention, it is obvious that the same is not to be restricted thereto but is broad enough to cover all structures coming within the scope of the annexed claims.

What we claim is:

1. In an eyelash curling device, a stationary handle portion having a slotted part, a movable handle pivotally attached to the slotted part,

said movable handle being provided with a slot, a fixed jaw, a movable jaw mounted for movement to and from the fixed jaw, a link connected to the movable jaw and having a part located in the slots, each slot having an off-set end portion to receive the link whereby the link can be moved with the movable handle portion when the link is positioned in the off-set portion of the slot in the movable handle or else can be held immovable when the link is in the off-set portion of the slot in the stationary handle portion while the handle is swung on its pivot.

2. In an eyelash curling device, a stationary handle carrying a fixed jaw, a movable jaw mounted for movement to and from the fixed jaw, a movable handle pivoted on the fixed handle and being provided with a slot having an off-set portion, a link attached to the movable jaw and having a part located in the slot and being capable of movement to position it in the off-set portion of the slot, said link when located in the off-set portion of the slot being moved to actuate the movable jaw by manual pivotal movement of the movable handle.

3. In an eyelash curling device as provided for in claim 2, wherein the stationary handle is provided with a lateral segmental extension and the movable handle is pivoted in said extension, and said extension is provided with a slot in which the link is moved upon manual actuation of the movable handle.

4. In an eyelash curling device, a stationary handle having a laterally projecting segmental extension provided with an arcuate slot, a movable handle having a segmental head at one end pivoted in said extension and also provided with an arcuate slot, a movable jaw, a link attached to said jaw at one end and having its other end disposed in both of the slots, each of the slots having an off-set portion, arranged whereby the movable handle can freely pivot without movement of the link when the link is positioned in the off-set portion of the slot in the segmental extension and whereby the movable handle will actuate the link and cause it to move the movable jaw when the link is positioned in the off-set portion of the slot in the head of the movable handle.

5. In an eyelash curling device, a stationary handle carrying a fixed jaw, a movable jaw mounted on the stationary handle and movable to and from the fixed jaw, a link attached at one end to the movable jaw, a segmental extension projecting from the stationary handle, a movable handle pivoted to said extension, the movable

handle having a segmental head formed with an arcuate slot, the slot having an off-set portion at one of its ends, the extension on the stationary handle having an arcuate slot provided with an off-set portion at one of its ends, said off-set portion extending toward the pivot, the link having its second end disposed in the slots and capable of shifting movement into either of the off-set portions of said slots, whereby the link when shifted into one of said off-set portions will remain stationary while the movable handle is pivotally moved and whereby said link when positioned in the other off-set portion will be moved upon manual movement of the movable handle.

6. In an eyelash curling device, a stationary handle having a slot, a movable handle having a slot, a jaw-moving element in the form of a link having a portion fitted into said slots, each of the slots having an off-set end portion whereby the link when fitted into one of said off-set portions,

will permit free pivotal movement of the movable handle without causing movement of said link.

7. In an eyelash curling device as provided for in claim 6, wherein the off-set portion of the slot in the movable handle is arranged to cause movement of the link when the link is fitted into said off-set portion. 5

8. In an eyelash curling device, a stationary handle and a movable handle, the movable handle having a segmental plate at one of its ends, a clevis carried by the stationary handle in which the plate on the movable handle is pivoted, the plate having an arcuate slot provided at one end with an off-set portion, the clevis having an arcuate slot provided at one end with an off-set portion, a jaw-actuating link having an end located

10
15

in both slots and adapted to have said end disposed in either of the off-set portions of the slots.
